METHOD OF FINISHING GEARS

Oliver G. Simmons, Lakewood, Ohio

Application April 27, 1935, Serial No. 18,676

4 Claims. (Cl. 90—2)

This invention relates to a method and means for finishing gears by subjecting the gears to a combined and simultaneous burnishing and shaving operation.

- 5 An object of the invention is to provide an improved and novel method and means for finishing gears with a high degree of accuracy and with the desired surface smoothness, compactness and finish.
- 10 Another object is to provide an improved and novel method and means for finishing gears quickly and economically and with a high degree of accuracy and the desired surface smoothness, compactness and finish.

- 15 Another object is to provide an improved and novel method and means for finishing gears quickly and economically and with a high degree of accuracy and the desired surface smoothness, compactness and finish by means of a combined 20 and simultaneous burnishing and shaving operation.

- 25 Another object is to provide an improved and novel method and means for finishing both external and internal gears quickly and economically and with a high degree of accuracy and the desired surface smoothness, compactness and finish by means of a combined and simultaneous 30 burnishing and shaving operation.

- 35 Another object is to provide an improved and novel method and means for finishing gears by a combined burnishing and shaving action, which quickly, economically and by means of a single operation refines the gear teeth to a high degree of accuracy, while simultaneously 40 burnishing the working face surfaces of the teeth.

- 45 Another object is to provide a method for simultaneously shaving and burnishing gears, wherein the burnishing pressures usually required are substantially reduced.

- 50 A further object is to provide a method for finishing gears by a combined burnishing and shaving action, which does not require in its practice expensive special machines.

- 55 Another object is to provide an improved tool or cutter in the form of a gear, for simultaneously burnishing and shaving gears to finish the same quickly, economically and with a high degree of accuracy and the desired surface smoothness, compactness and finish.

- 60 Further and additional objects and advantages residing in the invention will become apparent during the detailed description that is to follow of embodiments thereof.

Referring to the accompanying drawing,

Fig. 1 is an end elevational view of a plurality

of helical cutters embodying the invention arranged in intermeshing relation with a helical work gear, one of the cutters being mounted upon the spindle of a conventional milling machine or other machine tool, while the other cutters and the work gear are mounted upon shafts arranged in an attachment, such as is shown in my co-pending application, Serial Number 9,824, filed March 7, 1935, and which is secured to the table of the machine.

Fig. 2 is a side elevational view of one of the cutters shown in Fig. 1.

Fig. 3 is a detached and somewhat schematic side elevational view of the three cutters shown in Fig. 1, said view being on a reduced scale and illustrating the cutters arranged one above the other to show the manner in which the circular grooves formed therein from end to end of the cutters are staggered so that the three cutters combined have a multiplicity of cutting edges 20 which, when the cutters are rotated in mesh with a work gear, will take a multiplicity of bites or cuts in the gear extending from end to end of the gear and lying very closely adjacent to each other or actually overlapping each other.

Fig. 4 is a fragmentary developed sectional view through one of the teeth of the work gear illustrating diagrammatically the action of the cutting edges of the cutters upon the working face surface of the tooth of the gear, and

Fig. 5 is a view similar to Fig. 3, but illustrating modified forms of cutters from those shown in Fig. 3.

The present requirement for gears of high accuracy and finish, especially gears which are to be 35 used in motor vehicles, has necessitated further finishing operations upon the gears after they have been cut.

This further finishing of the gears has been carried out heretofore by means of a number of 40 separate operations, namely, by a shaving operation to remove and correct irregularities and errors in the gear teeth occasioned by inaccurate cutting of the gears, and by a separate burnishing operation to compact, smooth and polish the 45 working face surfaces of the gear teeth.

It will be evident that the practice involving separate shaving and polishing operations is necessarily slow and uneconomical.

Machines have been produced and are now 50 being used for the purpose of subjecting the gears to the shaving operation referred to. However, generally these machines impart to the work gears and to the tools or cutters compounded relative movements, usually consisting of relatively 55

rotating the work gears and cutters in mesh and at the same time imparting to the cutters and work gears relative long, lateral and linear movements to produce the shaving action of the cutters upon the work gears. These special machines, because of the compounded movements which they must impart to the cutters and work gears, are relatively complicated and expensive, in view of the single purpose for which they are used, and, in addition, they are relatively slow in operation.

Certain of the machines referred to are constructed so that the axes of the cutter and work gear are arranged in non-parallel relationship, wherefore the cutter has merely a tangential point contact with the work gear. It is necessary in such machines to impart long relative linear and lateral movements to the cutter and gear axially of the latter, to cause the tangential point contact of the cutter with the gear to move across the working face surfaces of the gear teeth from end to end thereof in order to cut cylindrical surfaces thereon.

Such machines are not adapted to operate upon internal gears because of the necessary lateral and linear movements of the cutter completely across the face of the gears, since the attaching flanges of the internal gears and the supports to which the flanges must be connected, restrict the operating space within the internal gears and interfere with the compounded relative rotative and long lateral and linear movements between the cutters and the work gears. The same condition exists in connection with gears formed on spline shafts, because the flanges or shoulders on the shafts adjacent to the gears interfere and prohibit the imparting to the cutters and work gears the compounded relative movements referred to. Likewise, the shaving of the gears of cluster gears cannot be carried out on these machines for the same reasons.

As previously stated heretofore the shaving operation must be followed by a separate burnishing operation, which not only increases the time and cost of finishing the gears, but requires separate burnishing apparatus therefor.

It is desired by means of the present invention to provide a method and means which may be used for finishing gears of different types, as for example, spur or helical external and internal gears, cluster gears, gears on spline shafts, herringbone gears and other types of gears to a high degree of accuracy, smoothness, compactness and finish, quickly and economically, by means of a single operation, and wherein the use of special complicated machines is eliminated since during the operation it is not necessary to impart to the cutters and work gears, in addition to the movement of rotation and a radial pressure feed movement, long lateral or linear relative movements therebetween, to cause the cutting edges of the former to cut or bite into the working face surfaces of the teeth of the work gears from end to end of the gears. In attaining the ends sought, the present invention contemplates the provision of combined burnishing and shaving cutters in the form of gears, which need only be rotated in mesh with the work gears while being given a suitable pressure feed movement, although in certain instances it may be preferable to give the cutters a slight relative axial movement or to allow the same some axial play to shave and burnish simultaneously the complete working face surfaces of the teeth of the work gears from end to end thereof and with a high degree of accu-

racy, smoothness, compactness and finish, irrespective of the degree of error of spacing or of tooth form in the work gears after they have been cut.

In my copending application Serial No. 9,824, filed March 7, 1935, the invention disclosed therein contemplated burnishing and shaving cutters in the form of straight tooth, helical tooth or other types of gears corresponding to the types of work gears with which they are used, and provided around their circumferences with a multiplicity of helical grooves extending from end to end of the cutters in an axial direction and completely through the teeth thereof from the outside diameters of the cutters to the roots of the teeth, whereby the teeth of the cutters are provided with a multiplicity of cutting edges which act, when the cutters are rotated under pressure in mesh with the work gears, to shave the complete working face surfaces of the teeth of the work gears from end to end of the gears, due to the lead of the circumferential helical grooves, while the working face surfaces of the teeth of the cutters between the helical grooves act to simultaneously burnish the working face surfaces of the teeth of the work gears.

The invention disclosed in the present application differs from that disclosed in my aforementioned copending application Serial No. 9,824, in that the cutters are provided with a multiplicity of circumferential circular grooves arranged in spaced relation from end to end of the cutters as distinguished from the helical grooves referred to. In order that the cuts or shaving bites of the cutting edges provided in the cutters by the circular circumferential grooves will act upon the complete working face surfaces of the teeth of the gears and will migrate from end to end of the work gears, the spaced circular circumferential grooves in each cutter are staggered or offset with relation to the spaced circular circumferential grooves in the other cutters of the group of cutters acting upon the work gears. Therefore, since the cutters are each provided with a plurality or multiplicity of such spaced circumferential circular grooves and the grooves in each cutter are staggered or offset with respect to the grooves of the other cutters, the shaving bites or cuts taken in the work gears by the large number of cutting edges formed by the grooves will lie in closely juxtaposed relationship or will overlap and will extend from end to end of the working face surfaces of the teeth of the work gears.

In view of the fact that the cutters are each provided with a plurality of spaced circumferential circular grooves staggered or offset with respect to the grooves in the other cutters and extending completely through the teeth of the cutters from the outside diameter thereof to the roots of the teeth, it is necessary, to effect the simultaneous shaving and burnishing of the entire working face surfaces of the teeth of the work gears from end to end of the gears, to impart only a relative rotative movement to the cutters in addition to a radial pressure feed movement between the cutters and work gears, although it is perhaps preferable in some instances to allow a slight axial play to the cutters or to impart thereto a slight axial movement to cause a complete overlapping of the shaving or cutting bites taken by the multiplicity of cutting edges of the cutters in the working face surfaces of the teeth of the work gear. It will be understood, however, that since the cutting edges formed by the staggered circumferential circular grooves in

the cutters, act upon the working face surfaces of the teeth of the work gear in such close proximity to each other that any axial movement or axial play which the cutters have will be so slight as not 5 to interfere with the practice of the invention upon internal gears, spline shaft gears, cluster gears, or the like, particularly since the axes of the cutters and work gears are arranged in parallel relationship.

10 As previously stated, the invention may be practiced upon the usual burnishing machine, wherein the work gear and the burnishing gears are simply rotated in mesh under pressure, or it may be practiced by means of simple attachments 15 which can be mounted upon the ordinary milling machine, lathe, or other machine tool, inasmuch as any relative movement imparted to the cutters and work gear in addition to the rotative and pressure feed movements would consist simply in 20 a very slight axial movement or axial play.

In describing the invention in detail, reference will first be made to Figs. 1 to 4 inclusive of the drawing, wherein an external helical work gear is shown being simultaneously shaved and bur- 25 nished by means of a plurality of helical cutters.

The helical work gear, indicated at 6, may be of either hand, any desired angle of helix, normal diametral pitch, normal pressure angle, and number of teeth.

30 The tools or cutters, indicated at 7, 8 and 9 respectively, are in the form of helical gears of the opposite hand from the work gear 6, but are of the same angle of helix, normal diametral pitch and normal pressure angle as the work gear.

35 Although the cutters may be of the same size and number of teeth as the work gear, it is preferable in the case of external gears to employ cutters which are of larger size and greater number of teeth than the work gear, because of the better 40 results thus obtained, due to the greater number of cutting edges, the increased burnishing and peripheral surfaces, and the longer wearing qualities of the cutters. Consequently the work gear 6 has been illustrated herein as of smaller size 45 and lesser number of teeth than the cutter 7, 8 and 9, it being noted that the cutters themselves are shown, by way of example, as all of the same size and number of teeth.

As previously stated, the cutters employed in 50 practicing the invention are provided with a plurality or multiplicity of spaced circumferential circular grooves extending from end to end of the cutters in an axial direction and completely through the teeth thereof from the outside diameters of the cutters to the roots of the teeth.

55 The cutters 7, 8 and 9 may be provided with the same number of spaced circumferential circular grooves or the various cutters may be provided with different numbers of the grooves. The cutters 7, 8 and 9 have been illustrated herein, by way of example, as each provided with four axially spaced circumferential circular grooves 10.

60 The circular grooves 10 preferably are spaced from end to end of the cutters in an axial direction and should be of sufficient number to form a great multiplicity of cutting edges 11 and 12 on both of the working face surfaces of each of the teeth of the cutters. The great number of cutting edges 11 and 12 formed on the teeth of the cutters 7, 8 and 9 by the spaced circumferential circular grooves 10 act, when the cutters are rotated in mesh with the work gears under pressure, to 65 take a large number of closely arranged shaving cuts or bites in the working face surfaces of the 75 teeth of the work gears from end to end thereof.

The large number or multiplicity of cutting or shaving edges 11 and 12 on the cutters reduces the cutting or shaving force which must be applied to the cutters in shaving the work gears and enables the cutters to be used upon conventional burnishing machines or upon attachments mounted on conventional machine tools. 5

Reference to Fig. 3 of the drawing will show that the circumferential grooves 10 are spaced axially of the cutters 7, 8 and 9 with the grooves 10 and the cutting edges 11 and 12 formed thereby so arranged in the various cutters as to lie in staggered or offset relationship with respect to the grooves and cutting edges in the other cutters, wherefore the shaving bites or cuts taken by the 15 cutting edges 11 and 12 in the working face surfaces of the work gears will lie very closely adjacent to each other and will extend from end to end of the work gears. This arrangement enables the work gears to be shaved and burnished by the 20 cutters by simply rotating the cutters and work gears in mesh under pressure, although it is preferable in order to obtain better results and smooth accurate working face surfaces on the teeth of the work gears to allow a slight axial play to the 25 cutters or to impart a very small axial movement thereto, to cause the shaving cuts or bites to overlap.

As previously stated, the grooves 10 extend completely through the teeth T of the cutters 7, 30 8 and 9 from the outside diameters D thereof to the roots R of the teeth. The teeth T of the cutters are divided by the circular grooves 10 from end to end of the cutters into a plurality of separate small cutting and burnishing teeth, each 35 of which in the case of helical cutters, has two obtuse cutting or shaving edges 12 and two acute shaving or cutting edges 11. The working face surfaces of the teeth T between the grooves 10 form a plurality of burnishing surfaces which, 40 when the cutters are rotated in mesh with the work gear under pressure, act to burnish uniformly the working face surfaces of the teeth of the work gear from end to end of the gear simultaneously as they are being shaved. 45

It will be understood that the cutters 7, 8 and 9 may be employed upon the usual burnishing machine and run in mesh with the work gear under pressure to shave and burnish the working face surfaces of the teeth of the work gear. In 50 addition to practising the invention upon the usual burnishing machine, it might be practised by means of an attachment which could be secured to the table or slide of a machine tool, such as a milling machine, and corresponding 55 to the attachment shown in my said copending application Serial No. 9,824. The attachment shown in my said copending application carries two of the cutters and the work gear while the third cutter is mounted on the spindle of the 60 machine. Of course, the invention can be practised upon any apparatus capable of supporting a plurality of cutters in mesh with the work gear on axes parallel to the axis thereof and rotating the same while applying a radial pressure feed 65 therebetween.

It will be understood that the rotation of the cutters in mesh with the work gear causes the large number of cutting edges 11 and 12 formed by the plurality of staggered or offset circumferential circular grooves 10 to take small cuts or shaving bites in the working face surfaces of the teeth of the work gear, which cuts or shaving bites, due to the great number of staggered or offset cutting or shaving edges, lie so closely ad- 75

5 jacent one another as to substantially overlap or merge together and to extend from end to end of the work gear in an axial direction. It will be seen that should there be any intervals between the shaving cuts or bites a slight axial play or movement of the cutters during the operation would eliminate such intervals and would result in a complete overlapping of the shaving cuts or bites.

10 Inasmuch as the shaving bites or cuts taken by the cutting edges 11 and 12 are each exceedingly small, the chips being like powder or the filings from a fine file, wherefore only relatively small pressures are required, the cutters and 15 work gear may be rotated at high speeds, since relatively small torque is required to cause the cutters to perform their cutting or shaving action upon the teeth of the work gear. Also, during the rotation of the cutters in mesh with the work 20 gear under pressure, the working face surfaces of the teeth T between the grooves 10 rolling in mesh with the working face surfaces of the teeth of the work gear, act to burnish the latter and to provide the desired smoothness, compactness 25 and finish thereon. It has been found that, due to the combined shaving and burnishing action, the teeth of the work gear are uniformly compacted and smoothed from end to end of the gear with less pressure than is required where 30 a burnishing action only takes place.

The simultaneous shaving and burnishing of the working face surfaces of the teeth of the work gear to the desired high degree of accuracy and smoothness and compactness is, due to the 35 multiplicity of cutting edges 11 and 12 and the high speeds of rotation of the cutters and work gears, accomplished in a very short time.

Assuming that the three helical cutters 7, 8 and 9 each has thirty-one teeth, and, as illustrated, are provided with four spaced circumferential circular grooves 10, it will be seen that each tooth of each cutter is divided by the four grooves into no less than five small shaving and burnishing teeth, each of which has four cutting 45 or shaving edges. Therefore, since each tooth of each cutter is divided into five small shaving or burnishing teeth having four cutting edges each, each tooth of each cutter will have twenty cutting edges, and since each cutter has thirty- 50 one teeth it will have a total of 620 shaving or cutting edges, 310 being the edges 11 and 310 being the edges 12. The three cutters 7, 8 and 9 combined will, of course, have in the aggregate 1860 shaving or cutting edges to act upon 55 the working face surfaces of the teeth of the work gear.

On the basis of the shaving and burnishing operation consuming twelve seconds, and assuming that the cutters are rotated at a speed of 60 400 R. P. M. it will be obvious that the cutters will, during the twelve seconds required for the shaving and burnishing operation, each make eighty complete revolutions in mesh with the work gear, or a total combined number of 240 65 revolutions in mesh with the work gear.

In view of the multiplicity of cutting or shaving edges on each cutter and the aggregate large number of the cutting or shaving edges on the three cutters, it will readily be seen that the 70 working face surfaces of the teeth of the work gear are subjected to a great multiplicity of cutting or shaving bites when the work gear is run in mesh with the cutters and under pressure during the shaving or burnishing operation.

75 Referring to the fragmentary developed view

of the working face surface of one side of one of the teeth of the helical work gear 6, as illustrated in Fig. 4, the heavy lines *a* represent the cuts taken by the cutting edges formed in one of the cutters by the grooves 10, while the cuts taken by the cutting edges formed in the other cutters by the grooves 10 are represented by the lines *b* and *c*, respectively. It will be understood that the distances between the lines *a*, *b* and *c* are exaggerated in the showing of Fig. 4, and 10 actually the cuts represented by said lines would lie very closely adjacent each other so that a slight axial movement of the cutters would cause the cuts in practice to overlap. The action of the cutting edges 11 and 12 of the cutters upon 15 the working face surfaces of the teeth of the work gear is similar to the action of the cutting edges of the cutters upon the teeth of the work gear, as shown and described in my above mentioned copending application, Serial No. 9,824, 20 and it is believed need not be explained in great detail herein. The cutting action of the cutting edges of the teeth of the cutter can be compared to the cutting action which would take place when a knife edge is brought into contact 25 with a surface under pressure and successively moved with small increments of advance across the surface, with the engagement between the knife edge and the surface likened to a series of shearing chops. Since each cutter is provided with a multiplicity of cutting edges spaced axially of the cutter, and since the cutting edges in each cutter of the plurality of cutters are staggered with respect to the cutting edges of each of the other cutters, a great number of cuts 30 or shearing chops will be taken in the working face surface of the gear, and these cuts or chops will be so closely juxtaposed as to substantially 35 overlap. However, since the cutters are arranged to have axial play or can be given a slight axial movement, the cuts or chops taken by the cutting edges of the cutters in the working face surfaces of the teeth of the gear will overlap and extend from end to end of the teeth of the gear.

40 It will be seen that in the practice of the present invention gears can be finished in a minimum of time, since they are simultaneously shaved and burnished in a single operation.

45 Inasmuch as it is only necessary to give rotational movement to the intermeshed work gear and cutters, in addition to a radial pressure feed movement therebetween, while preferably allowing a slight axial play or imparting a slight axial relative movement to the cutters and gear, to simultaneously shave and burnish the work gear, the invention may be readily practiced and employed to simultaneously shave and burnish a 50 wide variety of gears, such as external and internal spur and helical gears, spline shaft gears, herringbone gears, and various other types of 55 gears.

60 In Fig. 5 of the drawing the cutters 13, 14 and 15 differ from the cutters 7, 8 and 9 shown in Figs. 1 to 3 inclusive, in that they are in the form of spur gears, while the circular grooves 16 are disposed in planes intersecting the axes 65 of the cutters at acute angles, whereas the grooves 10 are disposed in planes intersecting the axes of the cutters at right angles. The disposition of the grooves 16 at acute angles to the axes of the cutters has the advantage in the case of 70 spur cutters of forming more acute cutting edges 17 on the teeth of the cutters than would grooves arranged at right angles to the axes of the cutters. It will be understood that the cutters 13, 14 and 15 operate upon spur work gears in a 75

manner similar to the operation of the cutters 7, 8 and 9 upon helical working gears, and that the grooves 17 in the various spur cutters are staggered or offset, and extend from the outside 5 diameters of the cutters to the roots of the teeth thereof. The expression "cutters of gear form corresponding to the work gear" as used in the description and claims hereof means that the cutters and the work gear are all of spur, helical or other gear form as distinguished for example from the cutters being of helical form and the work gear of spur form.

Although two embodiments of the invention have been illustrated and described herein, it 15 should be understood that the invention is susceptible of various modifications and adaptations within the scope of the appended claims.

Having thus described my invention I claim:

1. The method of simultaneously shaving and 20 burnishing gears which comprises positioning a work gear in intermeshing relation with a plurality of cutters of gear form and each having a multiplicity of circumferential circular grooves extending through the teeth thereof and 25 forming a multiplicity of cutting edges and burnishing surfaces, the axes of the gear and cutters being arranged in parallel relationship, and then rapidly rotating said intermeshed gear and cutters while applying radial pressure therebetween to simultaneously shave and burnish the 30 working face surfaces of the teeth of the gear.
2. The method of simultaneously shaving and 35 burnishing helical gears which comprises positioning a helical work gear in intermeshing relation with a plurality of helical cutters having a multiplicity of circumferential circular grooves extending through the teeth thereof and forming a multiplicity of cutting edges and burnish-
3. The method of simultaneously shaving and 10 burnishing gears which comprises positioning a work gear in intermeshing relation with a plurality of cutters of gear form and each having a 15 multiplicity of circumferential circular grooves extending through the teeth thereof and forming a multiplicity of cutting edges and burnishing surfaces with the grooves of each cutter staggered or offset with respect to the grooves 20 of the other cutters, the axes of the gear and cutters being arranged in parallel relationship, and then rapidly rotating said intermeshed gear and cutters while applying radial pressure therebetween to simultaneously shave and burnish the 25 working face surfaces of the teeth of the gear.
4. The method of simultaneously shaving and 30 burnishing helical gears which comprises positioning a helical work gear in intermeshing relation with a plurality of helical cutters each 25 having a multiplicity of circumferential circular grooves extending through the teeth thereof and forming a multiplicity of cutting edges and burnishing surfaces with the grooves of each cutter offset or staggered with respect to the grooves 30 of the other cutters the axes of the cutters and gear being arranged in parallel relationship, and then rapidly rotating said intermeshed gear and cutters while applying pressure radially therebetween to simultaneously shave and burnish the 35 working face surfaces of the teeth of the gear.

OLIVER G. SIMMONS.
